UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE.

1,224,093.

Specification of Letters Patent. Patented Apr. 24, 1917.

Application filed January 13, 1916. Serial No. 71,820.

To all whom it may concern:

Be it known that I, JOHN F. O'CONNOR, a citizen of the United States, residing at Chicago, in the county of Cook and State 5 of Illinois, have invented a certain new and useful Improvement in Hand-Brakes, of which the following is a full, clear, concise, and exact description, reference being had to the accompanying drawings, forming a 10 part of this specification.

This invention relates to improvements in hand brakes and more particularly to hand brakes for railway cars and other vehicles.

Objects of the invention are to provide a 15 hand brake for railway cars and other vehicles of simple construction, having few parts compactly arranged, which may be operated by one hand, which is provided with automatically operated friction locking 20 means, and which may be released by a hand lever.

Other objects of the invention are to provide a hand brake of the character above described, which does not employ any foot or 25 hand operated locking pawls and which permits a brakeman at all times to have the use of one hand and both feet for supporting and steadyng himself on the car.

The invention, furthermore, consists in 30 the improvements in the parts and devices and in the novel combinations of the parts and devices herein shown, described and claimed.

In the drawing forming a part of this 35 specification, Figure 1 is an end elevation of a portion of a hopper car showing my improvements in connection therewith. Fig. 2 is an enlarged, vertical, sectional view taken substantially on the line 2-2 of Fig. 1 and 40 illustrating the interior of the improved hand brake. Figs. 3 and 4 are vertical, sectional views taken substantially on the lines 3-3 and 4-4 of Fig. 2, respectively. Fig. 5 is a detail, sectional view illustrating the 45 friction clutch or locking means and taken substantially on the line 5-5 of Fig. 4. And Fig. 6 is a detail view illustrating a different embodiment of the invention.

Referring to Figs. 1 to 5, inclusive, 50 denotes the end wall of the car to which my improved hand brake A is attached, and 11 designates the chain for operating the brakes.

The brake mechanism proper, as shown, 55 comprises a base casting 12 and a shell or

casing 13, each of said members being provided with a plurality of flanges 14-14 by which the same are adapted to be secured to the car as by rivets 15. The chain 11 is attached at its upper end by a rivet or bolt 16 to a winding drum or windlass 17 which is rotatable about a horizontal axis, said drum or winding member 17 having integral trunnions 18 and 19 at each end, the trunnion 18 being mounted in a suitable hub or bearing 20 formed on the outer face of the shell or casing A. The trunnion 19 is mounted in a shiftable or rockable bearing 21 which is formed in a lever 22 having a rounded end 23 rockably mounted in a similarly shaped lug or projection 24 formed on the inner face of the base casting 12, see Fig. 4. The drum casting 17 has preferably formed integrally therewith a ratchet or cog wheel 25, the latter being spaced mid-way between the outer end of the drum 17 and the trunnion 18, whereby enlarged bearings 26-26 may be formed integrally with the drum casting on opposite sides of the ratchet wheel 25, see Fig. 2. The ratchet 80 wheel 25 is provided with suitable teeth on its periphery with which is adapted to co-operate a dog or projection 27 on the manually operated lever 28, the latter being provided with a substantially right angled extension 29 at its upper end, the latter having formed integrally therewith a pivot 30 which is detachably seated in a correspondingly shaped recess 31 formed on the lower end of an oscillatable hanger 32. The 90 hanger 32 is provided with upwardly extending, hook shaped, forked extensions 33 which are adapted to be hooked over and rest upon said bearings 26-26 on opposite sides of the ratchet wheel 25. The normal position of the hanger 32 and the operating lever 28 is as shown in Fig. 3, where it will be noted the operating lever is disengaged from the wheel 25.

At its inner end, the winding drum 17 is provided with one element of a friction clutch in the form of a disk 34 having a beveled periphery 35 which is adapted to co-operate with a corresponding V shaped groove 36 in a fixed friction clutch member or friction shoe 37 which is in the form of an integral, sector shaped projection formed on the inner face of the base casting 12. A manually operated release lever 38 is provided, the same being formed integrally 110

with the rockable lever bearing member 22, as clearly appears in Figs. 2 and 4.

- The bottom of the casing 13 is provided with a suitable opening 39 to permit the entrance of the chain 11, as appears from Fig. 2. As clearly shown in Fig. 4, the members 12 and 13 are suitably recessed as indicated at 40 and 41 to permit oscillation of the lever 38 and the casing 13 is also provided with a suitable opening 42 to permit the proper manipulation of the operating lever 28 and hanger 32. The drum 17 is provided with a suitable helical groove 43 to accommodate the chain as it is wound thereon and said drum is also provided with an integral flange 44 to properly deflect the chain as the winding is started and prevent it from interfering with the operating mechanism.
- 20 The operation is as follows: The brakeman standing on the end ladder of the car pulls on the operating lever 28 thereby rocking it on the hanger 32 and engaging the teeth 27 with the teeth of the wheel 25.
- 25 As the oscillation is continued, the lever 28, hanger 32, ratchet wheel 25, winding drum 17 and disk 34 will be rotated until the lever 28 is prevented from further rotation by engaging the casing 13 at the upper edge 30 of the slot 42. The brakeman then may either release the lever 28 and thereby permit it to fall back to normal position or may return the same positively and again impart a partial rotation to the winding 35 drum, repeating these operations as necessary to effect the proper tensioning of the chain 11. Since tension is placed upon the chain 11 by the winding operation above described, it is apparent that the winding 40 drum 17 will be pulled downwardly and hence the friction disk 34 will be operatively engaged with the stationary friction shoe 37 whereby the drum and chain is automatically locked, as will be understood.
- 45 When it is desired to release the chain, the brakeman pulls the release lever 38, thereby rocking the lever 22 and shifting the inner trunnion 19 of the winding drum. This effects the disengagement of the friction 50 disk 34 from the friction shoe 37, thereby instantly releasing the chain.

From the preceding description, it will be noted that there are no projecting parts which could hit the brakeman suddenly during the release since all the parts are concealed with the exception of the operating lever 28 and the latter will, of course, remain idle during the release action. Furthermore, it will be noted that there is comparatively little wear on the bearing surfaces between the hanger 32 and bearings 26, since in the winding operation there is no relative movement therebetween and on the return of the hanger 32 and lever 65 28 to normal, there is no friction except

that incident to the mere weight of said parts. It will also be seen that the brakeman employs only one hand in either winding the chain or in releasing it, thus permitting him to steady himself effectively on the car and promoting his safety.

As will be understood by those skilled in the art, the effectiveness of the friction clutch arrangement may be varied by either or both of two ways, namely, by changing the diameter of the friction disk 34 and by varying the angle between the beveled or wedge shaped periphery of the disk. Increases of diameter of the disk 34 will increase the effectiveness of the clutch and increases in the acuteness of the angle between the peripheral faces of the disk 34 will produce a similar result and vice versa.

Referring to the modification shown in Fig. 6, 132 represents a hanger similar to 85 the hanger 32 and 128 the operating lever. The latter, instead of being provided with a tooth or pawl, is provided with a cam 127 which is adapted to engage the plain periphery of the wheel 125. The operation 90 will be readily understood from the prior description of the structure shown in the preceding figures.

Although I have herein shown and described what I now consider the preferred 95 means of carrying out my invention, the same are merely illustrative since it is obvious that various changes and modifications may be made in the details of construction without departing from the spirit 100 of the invention, and all such changes and modifications are contemplated as come within the scope of the claims appended hereto.

I claim.

1. In a brake of the character described, the combination with a chain winding member, of an operating lever for winding a chain upon said member, said lever being normally disengaged from said member, a 110 friction clutch associated with said member and adapted to automatically lock the same, and means for releasing the clutch.

2. In a brake of the character described, the combination with a chain winding member, and means for operating said member, of a friction clutch coöperable with said member to hold it in locked position, and means, separate from the first named means, for releasing said clutch.

3. In a brake of the character described, the combination with a chain winding member, and means for operating said member, of a friction clutch coöperable with said member to hold it in locked position, and a 120 release lever for disengaging the clutch elements.

4. In a brake of the character described, the combination with a chain winding member, and means for operating said member 130

- to tighten the chain, of a friction element movable in unison with said member, a stationary friction element coöperable therewith, said elements being actuated to frictional locking engagement by tension on the chain when the same is tightened, and means, separate from the first named means for disengaging said friction elements to release the chain.
- 5 5. In a brake of the character described, the combination with a chain winding member, an automatically operating friction means associated therewith for locking the same when the chain is tightened, and separate and individually operated levers, one for rotating said member to tighten the chain and the other for releasing the friction means.
- 10 6. In a hand brake for cars or other vehicles, the combination with a brake chain, and a horizontally arranged brake chain winding member, of a friction wheel on said member, and a stationary friction shoe with which the friction wheel is held in frictional engagement by the tension of the brake chain.
- 15 7. In a hand brake for cars or other vehicles, the combination with a brake chain, and devices for placing said chain under tension, of a friction clutch coöperable with said devices to automatically hold the chain in taut condition, and means, separate from said devices, for releasing said friction clutch.
- 20 8. In a brake for cars or other vehicles, the combination with a brake chain, of a movable member adapted to pull and tighten said chain, of automatically operating friction means associated with said member for holding the chain taut, and separate and individually operated levers, one for moving said member to tighten the chain and the other for releasing the friction means.
- 25 9. In a brake of the character described, the combination with a member for pulling on a brake chain, and devices for holding said member in locked position, of means for operating said member, said means including a rotatable wheel, a manually operated lever adapted to engage said wheel, and a hanger to which said lever is detachably pivoted, said hanger being detachably hooked over a support rotatable with said wheel.
- 30 10. In a brake of the character described, the combination with a member adapted to pull on a brake chain, and means for operating said member, of a fixed friction element, a second friction element coöperable therewith and movable in unison with said member, said friction elements automatically locking when the chain is under tension, and means for disengaging the friction elements to release said member, said means including a shiftable bearing for said mem-
- ber and a release lever for moving said bearing and thereby said member with said friction element movable in unison therewith.
- 35 11. A brake of the character described, comprising in combination, a member adapted to pull and tighten a brake chain, and means for operating said member, of a fixed friction element, a second friction element coöperable therewith and carried by said member, said friction elements automatically locking when the chain is under tension, and means for releasing said friction elements including a rockable bearing for said member and a release lever for rocking said bearing.
- 40 12. In a hand brake for railway cars and other vehicles having a member rotatable about a horizontal axis for tightening a chain, of means for rotating said member, said means including a normally depending operating lever normally inoperative with respect to said member, and a normally depending supporting member mounted on and carried by said rotatable member, said operating lever being pivoted to said supporting member.
- 45 13. In a hand brake for railway cars and other vehicles, the combination with a rotatable member adapted to pull and tighten the brake chain, of means for rotating said member, said means including a wheel fixed to said member, a hanger detachably hooked over bearings formed integral with said member, and an operating lever detachably pivotally connected to said hanger, said lever having means for engaging said wheel whereby, as said lever is pulled it engages said wheel and oscillates the latter, the hanger, wheel, and lever traveling in unison.
- 50 14. In a hand brake for cars and other vehicles, the combination with a chain tensioning member, and means for rotating the latter, of automatically operating friction means for locking said member, said means including a friction disk carried by said member, a shiftable bearing for said member, and a stationary friction element coöperable with said friction disk, and a lever for shifting said bearing to thereby disengage the friction disk from the stationary friction element.
- 55 15. In a hand brake for cars and other vehicles, the combination with a chain tensioning member, and means for rotating the latter, of automatically operating friction means for locking said member, said means including a friction disk carried by said member, a shiftable bearing for said member, and a stationary friction element coöperable with said friction disk, and a lever for shifting said bearing to thereby disengage the friction disk from the stationary friction element, said lever being formed integrally with said shiftable bearing.
- 60 16. In a hand brake for railway cars and

- 4
- other vehicles, the combination with a base plate having a stationary friction shoe, of a movable bearing member supported by said base plate, a casing having a bearing therein, 5 a chain winding drum having trunnions at its ends mounted respectively in said shiftable bearing and the bearing in the casing, a friction wheel movable in unison with said drum, said friction wheel being adapted to 10 coöperate with said stationary friction shoe, a wheel movable in unison with said drum, a hanger hooked over bearings formed integrally with said drum, an operating lever detachably pivoted to said hanger and adapted to coöperate with said wheel to rotate the 15 drum when the lever is pulled in one direction, and a release lever for shifting said shiftable bearing to thereby disengage the friction disk from the stationary friction 20 shoe.
17. In a hand brake for railway cars and other vehicles, the combination with a base plate having a stationary friction shoe, of a movable bearing member supported by said base plate, a casing having a bearing therein, 25 a chain winding drum having trunnions at its ends mounted respectively in said shiftable bearing and the bearing in the casing, a friction wheel movable in unison with said drum, said friction wheel being adapted to 30 coöperate with said stationary friction shoe, a wheel movable in unison with said drum, a hanger hooked over bearings formed integrally with said drum, an operating lever 35 detachably pivoted to said hanger and adapted to coöperate with said wheel to rotate the drum when the lever is pulled in one direction, and a release lever for shifting said shiftable bearing to thereby disengage the friction disk from the stationary friction 40 shoe, said hanger being forked and straddling said wheel.
19. In a brake of the character described, 65 the combination with a member adapted to pull and tighten a brake chain, and means for operating said member, of a fixed friction element, a second movable friction element coöperable therewith, pressure being 70 applied to said movable friction element through the instrumentality of said member to thereby force the movable friction element into tight engagement with the fixed friction element when the chain is under tension, 75 and means for releasing said friction elements including a shiftable support associated with said member to relieve the pressure therefrom on the movable friction element, and a release lever for shifting the 80 position of said support.
- In witness that I claim the foregoing I have hereunto subscribed my name this 10th day of January, 1916:
- JOHN F. O'CONNOR.
18. In a hand brake for railway cars and
